(57) **CLAIM**

The ornamental design for a dogs' hip support, as shown and described.

DESCRIPTION

FIG. 1 is a front perspective view of a dogs' hip support, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is an enlarged, perspective view of detail “8”, identified in FIG. 1.

In the drawings, the shorter, equal-length broken lines on the dogs' hip support depict stitching and form part of the claimed design. The longer, equal-length broken lines showing a dog depict environmental structure and form no part of the claimed design. All broken lines form no part of the claim.
